[57] **CLAIM**

The ornamental design for a computer keyboard holder, as shown and described.

DESCRIPTION

FIG. 1 is a top perspective view of a computer keyboard holder showing our new design, on a reduced scale, the broken line drawing of a computer video monitor is for illustrative purposes only and forms no part of the claimed design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and,

FIG. 7 is an opposite side elevational view thereof. The elliptical element in FIGS. 1-7 is shown broken away to indicate an indeterminate length.

FIG. 1

FIG. 6

FIG. 2

FIG. 7
